Primary Examiner — John Windmuller(74) *Attorney, Agent, or Firm* — Schwegman Lundberg & Woessner, P.A.(57) **CLAIM**

The ornamental design for a fenestration latch, as shown and described.

DESCRIPTION

FIG. 1 is a first perspective view of a fenestration latch, showing the new design.

FIG. 2 is a second perspective view of the fenestration latch of FIG. 1.

FIG. 3 is a front view of the fenestration latch of FIG. 1.

FIG. 4 is a back view of the fenestration latch of FIG. 1.

FIG. 5 is a first side view of the fenestration latch of FIG. 1.

FIG. 6 is a second side view of the fenestration latch of FIG. 1.

FIG. 7 is a top view of the fenestration latch of FIG. 1; and,

FIG. 8 is a bottom view of the fenestration latch of FIG. 1.

1 Claim, 3 Drawing Sheets(56)
